(57) **CLAIM**

The ornamental design for a chair, as shown and described.

DESCRIPTION

FIG. 1 is a top, front, right perspective view of a first embodiment of a chair embodying my new design;

FIG. 2 is a right side elevational view thereof, the left side elevational view being a mirror image thereof;

FIG. 3 is a front elevational view thereof;

FIG. 4 is a top plan view thereof;

FIG. 5 is a rear elevational view thereof;

FIG. 6 is a bottom view thereof;

FIG. 7 is a top, front, right perspective view of a second embodiment of a chair embodying my new design, the right side elevational view being identical to that shown in FIG. 2 and the left side elevational view being a mirror image of that shown in FIG. 2;

FIG. 8 is a front elevational view thereof;

FIG. 9 is a top plan view thereof;

FIG. 10 is a rear elevational view thereof; and,

FIG. 11 is a bottom view thereof.

The broken away portions shown in FIGS. 7-11 represent indeterminate width of the claimed design.
